UNITED STATES PATENT OFFICE.

ERNEST E. YAXLEY, OF CHICAGO, ILLINOIS.

CLOCK WINDING MECHANISM.

No. 922,550.

Specification of Letters Patent.

Patented May 25, 1909.

Application filed April 2, 1908. Serial No. 424,760.

To all whom it may concern:

Be it known that I, ERNEST E. YAXLEY, a citizen of the United States, residing at Chicago, in the county of Cook and State of Illinois, have invented a certain new and useful Improvement in Clock Winding Mechanism, of which the following is a full, clear, concise, and exact description, reference being had to the accompanying drawings, forming a part of this specification.

My invention relates to motors and particularly to that class of motors finding service in the operation of clocks, though I do not wish to be limited to the use to which 15 the device of my invention is put.

Specifically, my invention relates to that class of motors in which electro-magnetic mechanism is employed for the purpose of supplying the same with motive power.

As is well known by those skilled in the art, the armature of an electro-magnet, in one class of clocks, has hitherto established circuit through the electro-magnet when said armature had reached a retracted position, whereupon the armature was attracted, the circuit previously established by the armature being broken before the armature had reached its attracted position, the momentum of the armature being relied upon 20 to complete its forward movement. The armature in its forward movement, works against the force of a power device in the form of a spring or weight, whereby energy is stored that is employed in operating the 25 motor.

In accordance with one feature of my invention, I maintain the circuit of the armature closed until it has fully reached its attracted position, whereby momentum is not 30 relied upon to complete the forward movement of the armature. The magnet working upon its armature and power device throughout the forward movement of the armature, stores up energy in said device 35 that it may effect the operation of the motor.

My invention has for another of its objects the provision of suitable signal mechanism which may be set into operation when the source of current employed for energizing the magnet fails in its duty of operatively energizing the magnet.

I will explain my invention more fully by reference to the accompanying drawings,

showing several embodiments thereof, in which—

Figure 1 is a view in elevation with parts broken away, of a motor adapted to the operation of a clock, and including the apparatus of my invention, one form of signal being diagrammatically illustrated in electrical association with the source of current employed for operating the magnet. Fig. 2 is a sectional plan view on line 2 2 of Fig. 1. Fig. 3 is an enlarged view of a portion of the structure shown in Figs. 1 and 2. Fig. 4 illustrates so much of a motor mechanism as is necessary to illustrate another embodiment of one feature of my invention. Fig. 5 illustrates so much of a motor mechanism as is necessary to illustrate another embodiment of a feature of my invention. Fig. 6 illustrates so much of a motor mechanism as is necessary to illustrate still another embodiment of a feature of my invention.

Like parts are indicated by similar characters of reference throughout the different figures.

The motor mechanism that I have illustrated is adapted to the operation of clocks and includes a clock train *a* in suitable relation with the hands of a clock, all as is well understood by those skilled in the art. The initial wheel *b* of the train *a* is in the form of a ratchet wheel, to which torque is initially applied for the purpose of operating the balance of the train in suitable gear relation with the wheel *b*. Torque is applied to the wheel *b* by means of an actuating pawl *c*, which is, in turn, operated by a spring *d* (Fig. 1) or its equivalent, the weight *d'* (Fig. 4). The pawl *c* is pivoted upon an armature *e* and power is effectively exerted upon the pawl *c* by the spring *d* or the weight *d'* through said armature, it being understood that this power is effectively exerted during the time that the magnet *f* provided for the armature, is in open circuit.

When the armature has completed its normal receding movement from its electro-magnet, the circuit including the electro-magnet and a suitable source of current, as the battery *g*, is closed between the contacts *h* and *i*, as will be presently described, whereby the tension of the spring *d* is increased or the weight *d'* is lifted, for the purpose of renewing the power that is re-

quired to operate the motor. During the attraction of the armature this circuit is maintained closed, as I will now describe in connection with the structure shown in Figs. 1 and 3. To accomplish this result in the embodiment of the invention shown in Figs. 1 and 3, I enable the holding pawl or detent *k* to act upon the spring contact *i* in such a manner that when the actuating pawl *c* has moved the wheel *b* its predetermined arcual distance, preferably one tooth, the holding pawl will drop into engagement with a fresh tooth and permit the spring contact *i* to engage the contact *h* by reason of the resiliency of the spring contact *i*, the spring contact *i* having been placed under increased tension by reason of the depression of the detent *k* during the movement of the wheel *b* the space of one tooth. It will, therefore, be seen that in the embodiment of the invention shown in Figs. 1 and 3, the contact *i* practically travels with the detent *k*, so that when said detent engages a new tooth, it closes circuit through the magnet. In order to open the circuit, the spring *h* is lifted, which lifting operation takes place when the armature *e* has been fully attracted, it being understood that when the armature is fully attracted, the actuating pawl *c* has engaged a fresh tooth, the pawl, when dropping into engagement with a fresh tooth, permitting an agency to effect the elevation of the contact *h*, which agency is desirably in the form of an adjustable spring *l* that is sufficiently strong to overcome the tension of the spring *h*, said spring *l* preferably acting upon the spring *h* through the pawl *c* and a roller post *m*, constituting a cam element, carried upon said pawl, the spring *h* having its end suitably upturned for engagement with said post, whereby the pawl mechanism has cam engagement with said spring *h*. The upturned end of the spring *h* that engages the post *m* is so related to the surface of the tooth over which the nose of the pawl *c* rides, that during the time that the nose of said pawl is riding over said tooth surface the said tooth surface prevents the spring *l* from having operative lifting action upon the upturned end of the spring *h*, though during this movement the post *m* desirably does not leave the spring *h*. When the pawl has left the tooth surface over which it has ridden, the restraining influence of said tooth surface is removed, whereupon said pawl is brought into actuating engagement with the tooth over which it previously rode through the agency of the spring *l*, forming part of the pawl mechanism, which spring also lifts the contact *h* through the intermediation of said pawl and the post *m* carried thereby and engaging said spring *h*, so that the springs or contacts *h* and *i* are separated and are only separated when the pawl *c* has left the tooth surface over

which it has ridden and has dropped into fresh tooth engagement. After the pawl has newly engaged a tooth, the circuit of the magnet *f* then being open, the power device *d* or *d'* acts through the armature *e* to move the pawl *c* in a direction opposite to that in which it previously moved, whereby turning effort is applied to the initial wheel *b* by the power device *d* or *d'* to operate the motor train. At this point it should be stated that Figs. 1, 3, 4 and 6 show the parts in the position they occupy just after the magnet circuit is closed and just before the armature is started toward its magnet, the wheel *b* not yet having been actuated by the pawl *c* and the power device *d* or *d'*.

It should be understood in connection with Fig. 5 that the armature is almost fully retracted preparatory to a fresh closure of the magnet circuit.

The detent *k* operates to prevent the wheel *b* from turning in a direction opposite to that which it follows through the agency of the pawl *c* during the time that the pawl *c* is riding over a tooth, the detent *k* freshly engaging a tooth when the pawl *c* has turned the wheel *b* a step. During the time that the pawl *c* is turning the wheel *b*, the detent *k* rides over a tooth surface preparatory to a fresh tooth engagement, during which riding action of said detent the contact *i* is depressed, the contact spring *h* being inherently adapted to follow the spring *i* in its downward movement but being prevented from engaging the same, by reason of the engagement of the contact *h* with the roller *m*. It is desirable to preserve an approximately fixed distance between the springs *h* and *i* when they are separated, to which end I preferably dispose the upturned end of the spring *h* parallel with the surface of the tooth over which the detent *k* is riding. When the detent *k* has escaped the tooth surface over which it has ridden and drops into fresh tooth engagement, the spring *i*, by reason of its own resiliency, makes contact with the spring *h*, it being understood that the detent *k* is mounted upon the spring *i* and is free of direct mechanical engagement with the spring *h*.

When the circuit of the electro-magnet is opened, the contact terminal *i* is stationary. The contact *i* is preferably made movable, as has been described, in order to simplify the construction, for in the embodiment shown in Figs. 1 and 3, the contacts *h* and *i* may be moved relatively very quickly both in opening the circuit and in closing the circuit, a single pair of contacts only being required. However, features of my invention may be practiced, as shown in Fig. 5, where one pair of contacts *h'* *i'* is employed for opening the magnet circuit and another pair of contacts *h''* *i''* is employed for closing the circuit, the contacts of each pair being adapted for quick

relative movement, in performing their functions, the contact i^2 also performing the function of the detent k . Features of my invention may also be practiced as shown in Fig. 6, 5 where a single pair of contacts h^3 i^3 is employed adapted for quick relative motion in opening the magnet circuit and slow relative motion in closing the circuit.

The motor of my invention may be employed to cause the operation of other motors 10 in synchronism, conductors n (Fig. 1) being illustrated in parallel connection with the conductors leading to the contacts h and i and in circuit with magnets that may have 15 an office similar to that of the magnet f .

It may be desired to prolong the movement of attraction of the armature for the purpose of increasing the duration of the engagement of the contacts h and i , to which 20 end I provide a retarding device to delay the attraction of the armature, one form of such retarding device being illustrated in Fig. 4 in the form of a fan o . It may be particularly desirable to supply a retarding device 25 when there are motor magnets connected with the energizing circuit, as is suggested by the wires n in Fig. 1.

Referring to Fig. 1, I have illustrated a self-soldering heat coil p such as are commonly found in the market, which normally 30 holds a spring q under tension, said spring carrying a signal target r , though I do not wish to be limited to the form of signal nor to a visual signal. The heat coil p is in serial 35 relation with the battery g . If the battery should become sufficiently spent to prevent it from operatively energizing the magnet f , the contacts h and i will remain closed. The current from the battery, though reduced, 40 will be sufficient by reason of the long duration of its flow, to melt the solder of heat coil p in circuit therewith, whereupon the spring q will be released, so that the signal target r will be presented before an opening r^1 , where- 45 by the observer will be informed that the battery needs replenishment, it being understood that when the battery is replenished the spring q is reset into the position shown to reestablish the battery circuit previously 50 opened by the release of spring q and to conceal the signal.

In Fig. 4 I have shown a signal target s , which is not within the influence of the armature when the armature moves throughout its normal range, but which is lifted by the armature when said armature is retracted by the power device beyond its normal range of movement upon diminution or cessation of the energizing current, where- 55 upon the target s is presented before an opening t , thereby indicating to the observer that the battery needs replenishment or that the source of current is not in proper relation with the electro-magnetic mechanism.

60 While the signal device is shown in asso-

ciation with the improved motor mechanism of my invention, I do not wish to be limited to such association.

The extent to which the armature may recede is regulable by the adjustable back stop 70 u , so that the armature cannot be removed from the range of its magnet.

It is obvious that changes may readily be made in the device of my invention herein shown and particularly described without departing from the spirit thereof, and I do not, therefore, wish to be limited thereto, but

Having thus described my invention, I claim as new and desire to secure by Letters Patent the following:

1. Motor mechanism including a toothed wheel, pawl mechanism including a pawl adapted for engagement with the toothed wheel to turn the same, a power device operating upon and through the pawl to effect turning movement of the wheel, an electro-magnet serving, when energized, to operate upon the pawl mechanism to cause the pawl thereof to have fresh tooth engagement, and upon the power device to 90 replenish power therein, and switching mechanism governed by the pawl mechanism and permitted to close circuit through the electro-magnet when the pawl has caused predetermined movement of the wheel, said 95 pawl mechanism operating the switching mechanism to open circuit through the electro-magnet when the pawl has fresh tooth engagement, the pawl mechanism being out of operating relation with the switching mechanism during movement of the pawl to the position where it may have fresh tooth engagement, whereby circuit through the electro-magnet is maintained during such 100 movement of the pawl.

2. Motor mechanism including a toothed wheel, pawl mechanism including a pawl adapted for engagement with the toothed wheel to turn the same, a power device operating upon and through the pawl to effect 110 turning movement of the wheel, an electro-magnet serving, when energized, to operate upon the pawl mechanism to cause the pawl thereof to have fresh tooth engagement and upon the power device to replenish power 115 therein, a detent caused to have fresh tooth engagement with said wheel when the wheel has been moved a predetermined distance by the power device acting through the pawl mechanism, and switching mechanism governed by said detent and pawl mechanism and operated by the detent when said detent has fresh tooth engagement to close circuit through said electro-magnet and operated by the pawl mechanism when the pawl thereof has fresh tooth engagement to open circuit through the electro-magnet, the pawl mechanism being out of operating relation with the switching mechanism during movement 125 of the pawl to the position where it may have 130

fresh tooth engagement, whereby circuit through the electro-magnet is maintained during such movement of the pawl.

3. Motor mechanism including a toothed wheel, pawl mechanism including a pawl adapted for engagement with the toothed wheel to turn the same, a power device operating upon and through the pawl to effect turning movement of the wheel, an electro-magnet serving to operate upon the pawl mechanism to cause the pawl thereof to have fresh tooth engagement and upon the power device to replenish power therein, and switching mechanism having a part engaged by the pawl of the pawl mechanism adapted to be moved by the pawl mechanism to close circuit through the electro-magnet when the pawl of the pawl mechanism has fresh tooth engagement, the place of contact of the pawl with the engaged portion of the switching mechanism moving in a plane substantially parallel with the surface of the tooth over which the pawl moves when being actuated by the electro-magnet, whereby said portion of the switching mechanism is not operated until the pawl has fresh tooth engagement and the electro-magnet is maintained energized during the movement of the pawl to the position where it may have fresh tooth engagement.

4. Motor mechanism including a toothed wheel, pawl mechanism including a pawl adapted for engagement with the toothed wheel to turn the same, a power device operating upon and through the pawl to effect turning movement of the wheel, an electro-magnet serving to operate upon the pawl mechanism to cause the pawl thereof to have fresh tooth engagement and upon the power device to replenish power therein, a detent caused to have fresh tooth engagement with said wheel when the wheel has been moved a predetermined distance by the power device acting through the pawl mechanism, and switching mechanism operated upon by the detent when said detent has fresh tooth engagement to close circuit through said electro-magnet, said switching mechanism having a part engaged by the pawl of the pawl mechanism adapted to be moved by the pawl mechanism to close circuit through the electro-magnet when the pawl of the pawl mechanism has fresh tooth engagement, the place of contact of the pawl with the engaged portion of the switching mechanism moving in a plane substantially parallel with the surface of the tooth over which the pawl moves when being actuated by the electro-magnet, whereby said portion of the switching mechanism is not operated until the pawl has fresh tooth engagement and the electro-magnet is maintained energized during the movement of the pawl to the position where it may have fresh tooth engagement.

5. Motor mechanism including a toothed

wheel, pawl mechanism including a pawl adapted for engagement with the toothed wheel to turn the same, a power device operating upon and through the pawl to effect turning movement of the wheel, an electro-magnet serving, when energized, to operate upon the pawl mechanism to cause the pawl thereof to have fresh tooth engagement, and upon the power device to replenish power therein, and switching mechanism governed by the pawl mechanism and permitted to close circuit through the electro-magnet when the pawl has caused predetermined movement of the wheel, said pawl mechanism operating the switching mechanism to open circuit through the electro-magnet when the pawl has fresh tooth engagement, the pawl mechanism being out of operating relation with the switching mechanism during movement of the pawl to the position where it may have fresh tooth engagement, whereby circuit through the electro-magnet is maintained during such movement of the pawl, the pawl mechanism being out of actuating relation with the switching mechanism during the time the power device is operating upon the pawl mechanism, to avoid additional load upon the power device as said power device causes the movement of the wheel.

6. Motor mechanism including a toothed wheel, pawl mechanism including a pawl adapted for engagement with the toothed wheel to turn the same, a power device operating upon and through the pawl to effect turning movement of the wheel, an electro-magnet serving, when energized, to operate upon the pawl mechanism to cause the pawl thereof to have fresh tooth engagement and upon the power device to replenish power therein, a detent caused to have fresh tooth engagement with said wheel when the wheel has been moved a predetermined distance by the power device acting through the pawl mechanism, and switching mechanism governed by said detent and pawl mechanism and operated by the detent when said detent has fresh tooth engagement to close circuit through said electro-magnet and operated by the pawl mechanism when the pawl thereof has fresh tooth engagement to open circuit through the electro-magnet, the pawl mechanism being out of operating relation with the switching mechanism during movement of the pawl to the position where it may have fresh tooth engagement, whereby circuit through the electro-magnet is maintained during such movement of the pawl, the pawl mechanism being out of actuating relation with the switching mechanism during the time the power device is operating upon the pawl mechanism, to avoid additional load upon the power device as said power device causes the movement of the wheel.

7. An apparatus of the class described in-

- cluding an electro-magnet, a power device in which energy is stored by the electro-magnet when energized, pawl mechanism operable by said power device to enable the transmission of power therefrom to perform work, a toothed wheel acted upon by said pawl mechanism, a switching device for closing circuit through the electro-magnet, whereby energy in the power device may be 5 replenished, said switching device including a detent adapted for tooth engagement with said wheel, and acting, when brought into fresh tooth engagement, to occasion the closure of said circuit, and a switching device 10 for excluding the electro-magnet from circuit and operated by the pawl mechanism when the pawl of the pawl mechanism drops to engage a fresh tooth, said switching devices including a contact spring common thereto, the contact governed by the detent being also in the form of a spring and moved by the detent as the detent rides over a tooth, the common contact spring possessing resiliency that enables it to follow its companion contact spring but prevented from moving into engagement with said companion contact spring by the pawl mechanism, whereby the two contact springs are in close relation when the detent has dropped 15 to engage a fresh tooth, whereby engagement between said contact springs is quickly effected when said detent drops to engage a fresh tooth.
8. An apparatus of the class described including an electro-magnet, a power device in which energy is stored by the electro-magnet when energized, pawl mechanism operable by said power device to enable the transmission of power therefrom to perform work, a toothed wheel acted upon by said pawl mechanism, a switching device for closing circuit through the electro-magnet, whereby energy in the power device may be 20 replenished, said switching device including a detent adapted for tooth engagement with said wheel, and acting, when brought into fresh tooth engagement, to occasion the closure of said circuit, and a switching device for excluding the electro-magnet from circuit and operated by the pawl mechanism when the pawl of the pawl mechanism drops to engage a fresh tooth, said switching devices including a contact spring common thereto, the contact governed by the detent being also in the form of a spring and moved by the detent as the detent rides over a tooth, the common contact spring possessing resiliency that enables it to follow its companion contact spring but prevented from moving into engagement with said companion contact spring by the pawl mechanism, whereby the two contact springs are in close relation when the detent has dropped 25 to engage a fresh tooth, whereby engagement between said contact springs is quickly effected when said detent drops to engage a fresh tooth.
9. An apparatus of the class described including an electro-magnet, an operating circuit therefor, a power device in which energy is stored by the armature of the electro-magnet when attracted, mechanism operable by said power device to enable the transmission of power therefrom to perform work, switching mechanism for excluding the electro-magnet from circuit and operable when the power device has transmitted energy replenished therein by the electro-magnet to close circuit through the electro-magnet, whereby energy in the power device may again be replenished, and signal mechanism whose operation is controlled by the electro-magnet and which operation is permitted by the electro-magnet only when the electro-magnet fails to respond to that 30 operation of the switching mechanism normally adapted to include the electro-magnet in circuit.
10. An apparatus of the class described including an electro-magnet, an operating circuit therefor, a power device in which energy is stored by the armature of the electro-magnet when attracted, mechanism operable by said power device to enable the transmission of power therefrom to perform work, said mechanism including said armature, switching mechanism for excluding the electro-magnet from circuit and operable 35 when the power device has transmitted energy replenished therein by the electro-magnet to close circuit through the electro-magnet, whereby energy in the power device may again be replenished, and signal mechanism whose operation is effected by the armature of the electro-magnet when said armature is retracted beyond its normal range by the power device.

In witness whereof, I hereunto subscribe my name this 28th day of March A. D., 1908.
